UNITED STATES PATENT OFFICE.

GEORGE W. KNADLER, OF PHILADELPHIA, PENNSYLVANIA.

DESIGN FOR A BODY FOR DELIVERY-WAGONS.

SPECIFICATION forming part of Design No. 28,035, dated December 14, 1897.

Application filed October 23, 1897. Serial No. 656,216. Term of patent 7 years.

To all whom it may concern:

Be it known that I, GEORGE W. KNADLER, a citizen of the United States, residing in the city and county of Philadelphia, in the State of Pennsylvania, have invented and produced 5 a new and original Design for Delivery-Wagon Bodies, of which the following is a specification.

The object of my invention is to produce a 10 design for a wagon body intended for transportation of merchandise, the side and rear walls or panels of which wagon body shall be provided with a new and pleasing ornamental pattern in relief, as a result of which the 15 said body presents a striking and handsome appearance.

Referring to the accompanying illustration which represents in perspective a wagon body the side and rear walls or panels of which embody 20 my design, it will be observed that the central portion of each of said panels or walls is occupied by a circular figure *a* of large diameter.

The said central circular figures are raised 25 above the surface of the body portions of said panels, so that said figures are in relief, so to speak, upon said panels.

On each panel a large number of lines of light beading *b* extend radially from the said 30 central figure, said lines of beading being disposed as to their inner ends equi-distant from each other, and being of such depth or thick-

ness that their crests or outer faces are practically flush with the raised outer face of the central figure *a* from which they radiate.

35

The outer extremities of the radial lines of beading *b* of the side panel, terminate in contact with frames or lines of molding which bound said wall or panel.

The molding *c* which extends along the 40 lower edge of the panel is straight and approximately horizontal,—the vertical moldings *c'* at the sides of the panel are perpendicular to the molding *c*,—while the molding *c''* at the upper edge of the panel follows the 45 trend of the adjacent edge of the roof.

The rear panel has a corresponding straight molding *c* at its lower edge, and a molding *c''* in the vicinity of its upper edge, said molding *c''* being slightly arched upward to follow 50 the curvature of the rear end of the roof.

Having thus described my invention, I claim and desire to secure by Letters Patent—

The design for the body of a delivery-wagon, 55 substantially as herein shown and described.

In testimony that I claim the foregoing as my invention I have hereunto signed my name this 14th day of October, A. D. 1897.

GEO. W. KNADLER.

In presence of—

F. NORMAN DIXON,
THOS. K. LANCASTER.
